UNITED STATES PATENT OFFICE.

JOSEPH C. DUNHAM, OF OKLAHOMA CITY, OKLAHOMA, ASSIGNOR TO THE SPRING GRUV-METAL WEATHER STRIP COMPANY, OF OKLAHOMA CITY, OKLAHOMA, A CORPORATION.

WEATHER STRIP.

Application filed November 2, 1922. Serial No. 598,536.

To all whom it may concern:

Be it known that I, JOSEPH C. DUNHAM, a citizen of the United States, residing at Oklahoma City, in the county of Oklahoma and State of Oklahoma, have invented a certain new and useful Improvement in Weather Strips, of which the following is a specification, reference being had to the accompanying drawings.

10 The invention provides simple and effective means in the way of a weather-strip of novel construction for preventing the passage of air, dust, water and other substances between the window-sash and the window-frame; and for the easy and quick removal of the lower sash and said weather-strip from the frame.

15 Another object of the invention is to provide means for securely holding the window or other enclosure in place in any and all kinds of weather, taking up the play between the sash and the frame caused by shrinkage, and also allowing for their expansion caused by swelling.

20 The invention, novel features, details of construction and combination of parts will be hereinafter more particularly set forth, illustrated in the accompanying two pages of drawings, and pointed out in the appended claims.

25 Referring to the drawings forming a part of this application,

Figure 1 is an elevational view of the inside of the upper and lower sash and the inside view of the window-frame surrounding them, installed with a weather-strip, showing the cross-section lines A—A, B—B and C—C.

30 Figure 2 is a sectional view of a portion of the top cross-section of the window-frame above the upper sash, and a portion of the upper sash shown on a line A—A as shown in Figure 1, and showing the weather-strip as viewed horizontally.

35 Figure 3 is a perspective view of the improved weather-strip.

40 Figure 4 is a sectional view of a portion of the side of the window-frame surrounding the lower sash shown on a line C—C as shown in Fig. 1, and the weather-strip as viewed from a vertical position.

45 Figure 5 is a sectional view of a portion of the side of the window-frame opposite the upper sash, and a portion of the upper sash on a line B—B as shown in Fig. 1, and

a portion of the weather-strip as viewed from a vertical position.

Figure 6 is a perspective view of a portion of the sill, a portion of the jamb, a portion of the lower sash, a front-stop with 60 screws holding the sash in place, and the lower sash partially raised.

Figure 7 is a perspective view of the same, showing the screws and front-stop removed, and used with Figure 6 and Figure 8 to 65 show the easy and quick removal of the sash and weather-strip.

Figure 8 is a perspective view of the same showing the removal of the sash and weather-strip more nearly effected, and the 70 location in the side of the jamb of the sheet metal spring used back of the weather-strip to force said strip in place.

Figure 9 is a sectional view of a portion of the jamb opposite the upper sash, and a 75 portion of the side of said sash, and the weather-strip, and the sheet metal spring forcing said strip in place.

Figure 10 is a perspective view of a portion of the upper sash showing a hole there-in near the top, and a portion of the weather-strip showing a bulged raised portion in the said strip to fit into said hole when said sash is fully raised.

Figure 11 is a sectional view of the 80 weather-strip showing the bulged or raised portion in said strip intended to fit into a hole in the upper sash to hold said upper sash in a closed position when fully raised.

Fig. 12 is a sectional view of a portion of 85 the lower cross-section of the lower window frame, and a portion of the cross bar of the lower sash showing a similar but inverted view of the said weather strip as shown in Fig. 2.

90 Like characters of reference designate like parts in all the figures.

The window shown in Figure 1 has the usual parts: sill, jambs and lintel, and includes the inner casing or frame 1, the upper 100 sash 2, the lower sash 3, the front-stop 4, and screws 5 holding it in place.

95 The improved weather-strip 6 is of sheet metal, for example sheet brass, or sheet bronze, or other sheet metal of good spring 105 quality; or it may be made of sheet zinc, and when so made, may be used alone, or it may have a curved or bent strip 16 of sheet brass, sheet bronze, or other sheet metal of good spring quality back of said sheet zinc strip 110

6, the whole length thereof, or shorter strips of said curved or bent sheet metal may be attached to said jamb in back of said sheet zinc strip, with nails or other permanent holding members, and said strip or strips being curved or bent slightly away from said frame and toward the sash, forces said weather-strip of said sheet zinc in place against the sash and into the larger and 10 smaller grooves 11 and 12 in the sash.

In Figure 3 is shown the form of the weather-strip. Near one end is shown a portion of the strip curved up at right angles with the body of said strip as shown at the 15 nail 8 Figure 5, and on the opposite side of the body of the strip from the window-sash, said curved end being inserted into a small groove 13 in the jamb. In the lintel and the sill similar strips are preferably held in 20 place by nails 8 or other permanent securing members, disposed near the curved or flanged ends and passed through said strips into the frame; and each strip has a flat portion or body bent slightly away from said jamb and 25 toward the sash and ending in a shoulder 14 and between said shoulder 14 and shoulder 15 the metal in said strip is curved or cupped oppositely to said first mentioned curved end, so as to form a loop 10 fitting into a 30 larger groove 11 in said sash; from said shoulder 15 to the beginning of the curved end 9 the strip extends substantially in a straight line; the other end 9 of said strip as distinguished from 7, is curved oppositely 35 to said first end 7, and towards the sash and on the same side of said strip as said loop 10, and said end 9 fits into the smaller groove 12 in said sash.

Back of said weather-strip of sheet zinc, 40 when so made, and between said strip and the jamb, a short distance from said end 7 and nail 8 is placed a strip 16 of said sheet metal of good spring quality held in place in said jamb by nails 17 or other permanent holding members, so as to force said strip of sheet zinc into place against said sash and into the larger and smaller grooves, 11 and 12 in said sash. Instead of having the strip 45 running the full length of said weather-strip and disposed in back thereof, a series of similar, but shorter strips may be used in the same way but at intervals of approximately 12 inches apart, attached to the jamb back of said sheet zinc strip with nails 17, or 50 other permanent holding members, and for the same purpose as indicated—to force the said sheet zinc weather-strip against the sash and the respective elements thereof into place into said larger and smaller grooves 55 11 and 12.

Both jambs are preferably equipped with the weather stripping described, as are also the lintel and the sill, the adjacent portion of the sashes being grooved to receive the 60 respective portions of the weather-strips.

The lower sash 3 and the weather-strips 6 thereof are further held in place by a front-stop 4, which is held in place by screws 5, or other permanent holding members.

As is shown in Figures 6, 7, and 8, by removing the screws 5 and the front-stop 4 and the nails securing the weather-strips which co-act with the lower sash, the sash and the weather-strip may be quickly and easily removed the better to adjust the 70 weights or clean around said sash without having to mar the frame and sash, and without bending out of shape the weather-strips.

At 18 of Figure 10 is shown a hole in the upper sash near the top thereof, and in the upper portion of the said strip a bulged or raised portion of said strip opposite to said hole in said sash when same is fully raised; the said bulged or raised portion being intended to fit into said hole in said sash when 80 fully raised so as to hold the said upper sash in place and in a closed position.

The preferred embodiment of the invention is disclosed in the drawings consisting of two pages, and set forth in the specifications, but it will be understood that any modification within the scope of the claimed invention may be made in the construction without departing from the principle of the invention or sacrificing any of its advantages. 90

Having thus described the invention, what is claimed, and desired to be secured by Letters Patent, is—

1. In combination with a window frame and sash, a sheet-metal weather-strip, formed so as to have a portion near one side edge turned down at right angles to the body of said strip, a portion near the other side edge turned up at right angles to the body of said strip, one of the edges fitting into a groove in the jamb, said strip adjacent said edge being secured to the jamb by permanent holding members, the other edge fitting into a groove in the sash, and said strip bent 100 towards the sash and having a portion pressing against the sash. 105

2. A sheet-metal weather strip, formed so as to have a portion near one of its side edges turned down at right angles to the body of said strip, a portion near the other side edge turned up at right angles to the body of said strip, one of said edges adapted to fit into a groove in a window jamb and a portion of the body adjacent said one edge adapted to be secured to the jamb by nails or other permanent holding members, and the other edge being adapted to fit into a groove in the sash, a loop in said strip intermediate said two curved edges adapted to fit into a second groove in the sash, said strip so bent as to enable it, when mounted in a window frame, to constantly push against the sash. 115 120 125

3. In combination with a window frame 130

- and sash, a sheet-metal weather strip formed so as to have a portion near one of its side edges turned down at right angles to the body of said strip, a portion near the other side edge turned up at right angles to the body of said strip, one of said edges adapted to fit into a groove and a portion of the body adjacent said one edge being adapted to be secured to the jamb by a stop carried thereby and by means securing the stop to the jamb, the other edge adapted to fit into a groove in the sash, said strip normally bent towards the sash so as to constantly press against the sash.
4. A sheet-metal weather strip formed so as to have a portion near one of its side edges turned down at right angles to the body of said strip, a portion near the other side edge turned up at right angles to the body of said strip, one of said edges adapted to fit into a groove in the jamb, and a portion of the body adjacent said one edge being adapted to be secured to the jamb by a stop carried thereby and by means securing the stop to the jamb, the other edge adapted to fit into a groove in the sash, a loop in said strip intermediate said two curved edges adapted to fit into a second groove in the sash, said strip so bent as to enable it, when mounted in a window frame, to constantly push against the sash.
5. In combination with a window jamb and a co-operating sash rail, a sheet metal weather-strip formed so as to have a portion near one of its side edges turned down at right angles to the body of said strip, a portion near the other side edge turned up at right angles to said body, one of said edges fitting into a groove in the jamb and the body portion adjacent said edge secured to the jamb by permanent holding members, the other edge fitting into a groove in the co-operating sash rail, said strip normally bent towards the sash so as to constantly press thereagainst, and a strip of resilient sheet metal disposed in back of the first described sheet metal strip and secured to the jamb by permanent holding members and having a portion inclined away from the jamb and constantly pressing against the first described strip.
6. In combination with a window jamb and a co-operating sash rail, a sheet metal weather-strip, formed so as to have a portion near one of its side edges turned down at right angles to the body of said strip, a portion near the other side edge turned up at right angles to said body, one of said edges fitting into a groove in the jamb and the body portion adjacent said edge adapted to be secured to the jamb by a stop carried thereby and by means securing the stop to the jamb, the other edge adapted to fit into a groove in the sash, said strip normally bent towards the sash so as to constantly press against the sash.
7. In combination with a stile of a window sash, a sheet metal weather-strip having a raised portion or bulge therein forming a button, said stile having a recess in the upper portion thereof, and said button being adapted to detachably engage in said recess to support said sash.
8. In combination with a window frame and sash, a resilient strip, having at the side edges of its body portion oppositely directed flanges, one normally disposed in a groove in a member of said frame and the other disposed in an adjacent sash rail, and also having a U-shaped portion between said flanges and extending into a groove in the respective sash rail, the strip being attached near one edge by securing means to the respective frame member, and, a resilient strip being interposed between the frame member and the first strip to force the latter into operative engagement with the sash rail.
9. In combination with a window frame and sash, a resilient strip, having at the side edges of its body portion oppositely directed flanges one normally disposed in a groove in a member of said frame, and the other disposed in an adjacent sash rail, and also having a U-shaped portion between said flanges and extending into a groove in the respective sash rail, the strip being attached near one edge by securing means to the respective frame member, and, a resilient strip being interposed between the frame member and the first strip to force the latter into operative engagement with the sash rail; and said weather-strip having at its upper portion a raised portion or bulge forming a button adapted to fit into a hole in the upper portion of the sash to hold said sash in raised position.

JOSEPH C. DUNHAM.
